[57] CLAIM

The ornamental design for an electrical cable, as shown and described.

DESCRIPTION

FIG. 1 is a perspective view of the electrical cable according to the present invention.

FIG. 2 is a left side view of the electrical cable shown in FIG. 1.

FIG. 3 is a right side view of the electrical cable shown in FIG. 1.

FIG. 4 is a top view of the electrical cable shown in FIG. 1. FIG. 5 is a bottom view of the electrical cable shown in FIG. 1.

FIG. 6 is a front view of the electrical cable shown in FIG. 1; and,

FIG. 7 is a rear view of the electrical cable shown in FIG. 1.

The cable is shown broken away in FIGS. 1-5 to indicate indeterminate length.
